APPARATUS FOR CLEANING BOTTLES

Paul S. Pittenger, Philadelphia, Pa., assignor to
 Sharp & Dohme, Incorporated, Philadelphia,
 Pa., a corporation of Maryland

Application March 16, 1931, Serial No. 522,927

7. Claims. (Cl. 15—20)

This invention relates to cleaning bottles by blowing them just prior to filling them and includes both method and apparatus. More particularly the invention relates to apparatus for blowing bottles one at a time by means of an air jet from a tube inserted successively into the mouth of each bottle and then ejecting the bottle from the blowing machine.

It is customary to subject bottles used for pharmaceutical preparations, foods, etc. to a cleaning operation immediately prior to filling them. In general this cleaning is some sort of wet wash treatment. Such cleaning treatments require careful supervision to make certain that the water used in the final rinse is clean water, and, furthermore, to see that all foreign particles are removed from the bottles and that the bottles are thoroughly dried before being filled. Such methods of cleaning are time-consuming and the labor charges are considerable.

I have found that it is not necessary to wash the bottles before filling them if they are properly handled from the time of their manufacture up to the time that they are being filled. The bottles are not only clean but sterile when they leave the leir where they are annealed. I package them on leaving the leir in cartons or other containers in which they remain until just prior to filling them. Preferably the bottles are placed in the cartons in an inverted position. They may be stoppered although, if inverted, the mouth of the bottle is pressed against the bottom of the container with sufficient pressure to satisfactorily seal the bottle. Each carton or other container holds a dozen bottles, more or less, and the bottles are brought in the carton or other container directly to a conveyor which feeds them to the blowing apparatus of my invention from which they may be fed automatically to the filling machine. From the filling machine they are delivered to another container for final packaging, or, they may first be subjected to other treatment such as labelling, weighing, etc.

According to this invention the bottles are blown with a jet of air with sufficient force to remove any splinters of glass or other foreign particles which the bottles may contain. The air employed may be sterilized or it may be subjected to any other purifying or drying or heating treatment desired before being used for blowing the bottles. Tests have shown that bottles cleaned in this way are freer from germs, etc. than bottles which have been subjected to the ordinary wet cleaning treatment and they are also freer from foreign particles. They present

a better appearance due to the fact that their original gloss is not removed by my method of cleaning.

The preferred embodiment of the invention shown in the accompanying drawings is adapted for treating cylindrical bottles. With slight modification the apparatus shown may be adapted for handling and blowing bottles of other shapes. According to this preferred method, the bottles are fed by gravity from an inclined shelf 5 into a horizontal trough referred to herein as the bottle holder. While in the trough an air nozzle is inserted through the mouth of the bottle and the bottle is blown with air with sufficient force to remove all solid particles from the interior of 10 the bottle. The nozzle is generally merely the open end of an air tube. The bottle is then ejected from the trough and the air nozzle is withdrawn so that the trough is empty and ready to receive the next bottle to be treated. The 15 bottles are ejected on to an inclined conveyor which delivers them upright onto still another conveyor which delivers them to the filling machine or other treating apparatus.

The insertion of the air tube into the bottle and the action of the ejector are so synchronized that the whole operation takes the minimum of time. The insertion of the air tube and the forward and backward movement of the ejector are controlled by the operation of cams and the various operations are so co-ordinated that after the ejection of one bottle the ejector returns to the position in which it is adapted to receive another bottle and the air jet is withdrawn so that the next bottle to be treated falls into place with its neck 30 in the ejector-head, ready to be blown. The air tube is then inserted through the neck of the bottle and the bottle is blown and the ejector is then moved forward to remove the bottle from the bottle holder before the air tube is withdrawn. The ejector and air tube then move backward to their original position ready for the treatment of another bottle. The operation is simple and bottles may be blown at the rate of ten to one 35 hundred or more bottles per minute.

The invention will be further described in connection with the accompanying drawings, but it is intended and is to be understood that it is not limited thereto.

In the drawings:

Fig. 1 shows the blowing apparatus in perspective;

Fig. 2 is a detail showing the cam movement for the operation of the ejector and air tube;

Fig. 3 is a cross-section of the trough or bottle holder; and

Fig. 4 is a schematic plan view indicating how the bottles may travel in being removed from a container, blown and filled and then returned to a container.

The shelf 1 is an inclined shelf which feeds the bottles by gravity into the trough or bottle holder 2. While in this trough the bottles are blown with air and they are then ejected onto the belt 3 which conveys them from the blowing apparatus. Fig. 1 shows the bottles as being delivered from the belt 3 onto the belt 4 and the arrangements of the belts 3 and 4 are such that the bottle is stood upright on the conveyor 4 and it is thus delivered to the filling machine in an upright position. The guideboards 5 prevent the bottles from rolling off the conveyors 3 and 4.

As the bottle rolls into the bottle holder 2 the neck of the bottle fits into the ejector-head 6. The ejector-head is generally cylindrical but a portion on the side toward the shelf 1 is cut away as shown in detail in Figs. 2 and 3 so that the neck of the bottle rolls into the ejector-head and rests there while the bottle is blown and also while the ejector removes the bottle from the apparatus. Sufficient time elapses between the ejection of one bottle and the start of the blowing of the next bottle for this next bottle to be received in place with its neck in the bottle-holder.

The operation of the ejector and the air tube will best be understood by reference to Fig. 2. As soon as the bottle is in place the air tube 7 moves in through the neck into the bottle. There is an opening 8 in the butt end of the air tube. When the air tube is way in the bottle, i. e. when it is at the forward end of its stroke or in the in position, the opening 8 is brought into communication with the air supply line 9. Compressed air then passes through the line 9 and then by the opening 8 through the interior of the tube 7 into the bottle. The pressure of the air is sufficient to blow any foreign particles from the bottle.

After the bottle has been blown a sufficient length of time the ejector-head is set in motion. It moves to the left and ejects the bottle from the bottle holder onto the conveyor 3. The ejector-head 6 is fastened onto the ejector tube 10 and the lever arm 11 which actuates the air tube moves through the slot 12 in this ejector tube 10. When the ejector tube is at the end of its forward stroke the end 13 of the slot 12 presses against the lever arm 11 and holds the air tube in the in position until the ejector arm again moves backward. As soon as the air tube reaches the forward end of its stroke, i. e. as soon as it reaches the in position, the blowing of the bottle commences. After the blowing commences the ejector-head 6 begins its forward stroke. The bottle is blown continuously until the end of the forward stroke of the ejector-head 6, i. e. until the bottle has been ejected from the bottle holder. The air tube 7 and the ejector-head then move backward together, the backward movement of the lever arm 11 being controlled by the movement of the ejector tube through the pressure of the lever arm 11 against the end 13 of the slot 12.

The movements of the air tube and the ejector tube are controlled from the cam shaft 14 through the cams 15 and 16. The cam shaft 14 is driven by the pulley 17 through the pulleys 18 and 19. When the cams are in the position shown in Fig. 2 the air tube 7 has just reached the in position and the ejector tube has not yet commenced its forward stroke. The operation of the air tube is

controlled by the action of the cam 15 on the stud 20 which is fastened to the lever 21. The spring 22 tends to hold the lever 21 and thus the air tube in the out position and it returns the air tube to the out position when the ejector tube is at the end of its backward stroke. The position of the ejector tube is controlled by the cam 16 which operates on the stud 23 which is attached to the lever 24. The spring 25 tends to hold the ejector tube at the end of its backward stroke.

After a bottle has been received in the bottle-holder or trough 2 the air tube is moved into the in position as shown in Fig. 2 by the pressure of the cam 15 on the stud 20. This brings the opening 8 into communication with the air supply pipe 9 and the bottle is blown. As the cam shaft 14 rotates the cam 16 moves the ejector tube into the forward position and the bottle is ejected from the holder. At the end of the forward stroke the end 13 of the slot 12 in the ejector tube 10 presses against the lever arm 11 and holds the air tube in the in position while the cam 15 moves out of contact with the stud 20. Then as the cam shaft continues to rotate and the cam 16 completes its cycle, the ejector tube is returned to its original position by the spring 25 and the air tube is returned to the out position by the spring 22. The bottle is thus blown and then ejected from the bottle holder 2 onto the conveyor 3. The drawings show a belt 26 for driving the pulley 27 which drives the conveyor belt 3.

For the sake of simplicity Fig. 1 shows only a few bottles on the inclined shelf 1. In actual practice the bottles on the shelf will roll to the bottom of the shelf so that the bottom of the shelf will always be full and the next bottle to be blown will always be in contact with the bottle which is in the bottle-holder and actually being blown.

Fig. 4 shows in a diagrammatic way one method of handling bottles so that they are blown just prior to being filled. The bottles are filled into the container 30 from the lees at the bottle works. They are taken from this container and fed onto the conveyor or chute 31. This delivers them onto the inclined shelf 1. The stop-bar 32 lines the bottles up and they roll down the inclined shelf in regular order to the bottle-holder 2 where they are blown. Any foreign particles in the bottles are removed during the blowing operation. They are delivered from the bottle-holder 2 by the ejector onto the conveyor 3. From this conveyor they are stood upright on the conveyor 4. The conveyor 4 delivers them to the filling, stoppering and labeling machine or machines 33. This machine or machines in turn delivers them onto the conveyor 34 from which they are replaced by hand or machine into the original or another carton or container 35. Labelling, numbering and other operations may be interposed between the blowing operation and the filling operation or between the filling operation and the packaging operation in which the bottles are returned to a container, or the bottles may be subjected to other processing steps as desired, but it is understood that the bottle is subjected to the blowing step just prior to being filled, i. e. without appreciable delay during which the bottles might become contaminated with dust, etc. The bottles may pass directly from the blowing machine to the filling machine or they may be labelled or otherwise treated between the blowing operation and the filling operation.

The invention provides a dry cleaning treatment during which the bottles are blown with air

immediately prior to being filled, whereby foreign particles are removed from the bottles. Although the invention is described more particularly as applied to the treatment of cylindrical bottles by a process in which the bottles are fed by gravity into the blowing apparatus and then ejected horizontally onto the conveyor by which they are removed from the blowing machine, it is understood that the invention is not limited thereto but with appropriate modifications the blowing treatment may be applied to bottles which are other than round and the bottles may be fed to or removed from the blowing apparatus by positive means or by gravity or in any other suitable manner, as desired.

I claim:

1. In a bottle-treating machine, an ejector-head adapted to receive the mouth of a bottle, an air tube, an operating lever connected with the air tube and adapted to move it in and out of the bottle, an operating lever connected with the ejector-head and adapted to move it in a horizontal position and to eject the bottle from the machine, a cam shaft, and cams on the shaft for actuating the operating levers.
2. In a bottle-treating machine, an ejector-head adapted to receive a bottle, an operating lever adapted to move the ejector-head so as to eject the bottle from the machine, an air tube, an operating lever adapted to move the tube in and out of the bottle, an air supply pipe adapted to supply air to the air tube when it is in the bottle, a cam shaft, a cam for actuating each of the operating levers, the two cams being so timed that the ejector ejects the bottle after it has been blown.
3. In a bottle-treating machine, a bottle-holder, a shelf for feeding bottles by gravity to the bottle-holder, an air tube connected with means for moving it in and out of a bottle in the bottle-holder, an ejector head adapted to receive the mouth of a bottle when it is fed to the holder from the shelf, and means for moving the ejector-head so as to eject bottles from the bottle-holder, the ejector head and the air tube both being reciprocally mounted in a horizontal position on concentric axes in a line parallel with the axis of the bottle-holder.

4. In a bottle-treating machine, a bottle-holder, a shelf for feeding bottles by gravity to the bottle-holder, an air tube adapted to be inserted in a bottle when it is in the bottle-holder, an ejector tube adapted to receive the neck of a bottle when the bottle is in the bottle-holder, the bottle ejector and the air tube both being adapted to reciprocate in a horizontal position on concentric axes in a line parallel with the axis of the bottle-holder, and cam means for actuating both the air tube and the bottle ejector, the cams being so timed that the air tube is inserted in the bottle before the ejector moves the bottle out of the bottle-holder.

5. In a bottle-treating machine, a bottle-holder mounted on a horizontal axis adapted to receive a bottle for blowing, a bottle-ejector adapted to press against the top of the bottle below the neck, cam-actuated means adapted to move the bottle ejector on an axis parallel to the axis of the bottle-holder so as to eject the bottle from the bottle-holder, an air tube, cam-actuated means adapted to move the air tube on an axis concentric with the axis on which the bottle-ejector moves and to reciprocate the air tube through the ejector-head in and out of the bottle, and cam means so timed that the air tube moves forward into the bottle while the ejector-head is maintained at the end of its backward stroke.

6. In a bottle-treating machine, a bottle-holder, an air tube connected with means adapted to cause it to reciprocate in and out of a bottle in the bottle-holder and an ejector to remove a bottle from the bottle-holder, the air tube and ejector being reciprocally mounted on concentric axes.

7. In a bottle-treating machine, an ejector head adapted to receive the mouth of a bottle, an air tube, means whereby air may be forced through said tube into the bottle only when the tube is in the bottle, an operating lever connected with the air tube and adapted to move it into and out of the bottle, an operating lever connected with the ejector head and adapted to move it to eject the bottle from the machine, and means for operating said levers.

PAUL S. PITTINGER.
